UNITED STATES PATENT OFFICE.

JOHN M. GILMORE, OF CHICAGO, ILLINOIS.

DENTAL TOOL-HOLDER.

1,108,570.

Specification of Letters Patent. Patented Aug. 25, 1914.

Application filed July 15, 1911. Serial No. 638,648.

To all whom it may concern:

Be it known that I, JOHN M. GILMORE, a citizen of the United States, residing at Chicago, in the county of Cook and State of Illinois, have invented a new and useful Improvement in Dental Tool-Holders, of which the following is a specification.

My invention relates more particularly to improvements in dental apparatus of the type involving a hand-piece, or holder, containing a rotary element adapted to be driven by either manual or machine power, and constructed to rotate tools of different constructions used in operating on teeth.

In performing certain operations upon teeth, it is necessary that very small, slender tools be used, as in the case of the treatment of pyorrhea where it is necessary to remove accumulations from the roots of teeth; and the conditions attending the use of such tools is oftentimes such as to cause them to become wedged between teeth or otherwise resistant to turning, with the result of causing the tool to break and oftentimes injuring the mouth of the patient. Furthermore, it is desirable that the extent of protrusion of the tools employed be variable relative to their supporting mandrels for enabling them to penetrate to the desired extent, but without protruding beyond the mandrels to any greater extent than is necessary.

My object is to provide a simple construction of dental apparatus of the type referred to by which breakage of the tool in use will be overcome and which will permit of the adjustment of the tool in its mandrel, and this I accomplish by the construction herein-after described.

Referring to the accompanying drawing Figure 1 is a view in elevation, partly sectional, of a common form of hand-piece equipped with my improvement. Fig. 2 is a view in elevation of one of the sections of the tool supporting mandrel shown in Fig. 1. Fig. 3 is a similar view of the other section of the mandrel. Fig. 4 is a similar view of the broach shown in Fig. 1, these three views considered together showing the parts illustrated therein in disassembled but related condition; and Fig. 5, an enlarged longitudinal section taken through the man-

drel and showing the parts illustrated in Figs. 2, 3 and 4 in assembled condition.

The hand-piece of a dental-engine in connection with which I have illustrated my invention is represented at 6, and as this hand-piece is of a well-known construction, description thereof is deemed unnecessary. It may, however, be stated that the member 7 located in the hand-piece at its outer end-portion is a rotary chuck which is driven from the flexible shaft (not shown) and serves to releasably clutch the tool-carrying mandrel to the driving power.

My improved mandrel, in its preferred embodiment, comprises telescoping sections 8 and 9, the section 8 being adapted to be inserted into the outer end of the hand-piece and into engagement with the clutch-member 7. Both of the sections 8 and 9 are tubular, the outer end of the section 8 being open and its inner end closed by a plug 10 rigid therewith and provided with a needle-extension 11 preferably of steel. The section 9 which is adapted to be inserted into the outer end of the section 8, has the end-portion thereof, which is insertible into the section 8, beveled as indicated at 12, the internal diameter of the section 9 being slightly larger than the diameter of the broach with which it is used, whereby the broach is readily insertible into, and withdrawable from, the mandrel; the desired freedom of vibration of the outer end of the broach is afforded; and the needle readily enters between the shank of the broach and the surrounding tube in the assembling operation. When it is desired to secure a tool to the mandrel, such for instance as the tool 13, which in the case illustrated is a spiral broach, the tool is inserted into the mandrel section 9 to cause its shank-portion to lie therein, and the section 9 with the broach 13 thus positioned therein is then inserted into the open, outer end of the mandrel-section 8, the operator in this operation holding the assembled tool and mandrel-section 9 firmly gripped between his fingers or by pliers. In thus assembling the section 9 and tool 13 with the section 8, the point of the needle 11 enters the space between the inner wall of the section 9 and the shank of the tool 13, thereby

wedging the needle and shank of the tool 13 against the wall of the section 9, with the result of holding the tool 13, needle 11 and mandrel-section 9 in frictional engagement.

It will be understood from the foregoing that should the broach 13, when in use, become wedged between teeth, or be caught in a cavity, the frictional engagement of the broach with the needle 11 and the mandrel-section 9 will permit of slippage of the tool with relation to the driving means in the hand-piece and thus prevent the broach from breaking. Manifestly the degree of wedging action produced by the needle 11 coöperating with the other parts as stated may be varied as desired by varying the pressure at which these parts are forced into wedging engagement with each other, and thus the resistance to slipping of the tool with relation to the driving means in the hand-piece may be varied, which is of especial advantage where tools of different strength are used. Furthermore, by my improved construction of mandrel the broach, or other tool, to be used, may be readily adjusted, as to its extent of protrusion beyond the mandrel, by merely varying the positioning of the broach in the mandrel-section 9 preliminary to the assembling operation, this being a desirable feature as the tools are very fragile and protrusion of the tool beyond the mandrel to a greater extent than the particular use to which the tool is put requires, is to be avoided. The needle-equipped mandrel-section 8 also has utility when used without the other section 9, as for instance when a wood-polishing point is to be employed, the point being insertible into the outer, open end of the section 8 and forced therein into engagement at its inner end with the point of the needle 11, causing the latter to penetrate the wood point and spread the inner ends thereof, thus wedging it in the mandrel.

By constructing a mandrel in accordance with my invention, the use of breaches in a dental engine for rimming or otherwise operating on root-canals is rendered possible without danger of breaking off the broach in the canal, as the slippage provided by my construction prevents the tool from breaking in the event of resistant strains on the broach tending to break it.

What I claim as new, and desire to secure by Letters Patent, is—

1. A mandrel for the purpose set forth, comprising telescoping tubes, the inner one of which is open at both ends and receives the tool to be secured to the mandrel, and wedging means secured to the other of said tubes for frictionally holding the mandrel-tubes and tool together, adapted to enter between the free end-portion of said tool and the wall of said inner tube, for the purpose set forth.

2. A mandrel for the purpose set forth, comprising telescoping tubes, the inner one of which is open at both ends for receiving the tool to be secured to the mandrel, said inner tube having a beveled inner end-portion, and wedging means carried by the outer tube for frictionally holding the tool and tubes together, said wedging means adapted to enter between the inner end-portion of said tool, and the wall of the beveled end of said inner tube, for the purpose set forth.

3. A mandrel for the purpose set forth, comprising telescoping tubes, the inner one of which is open at both ends for receiving the tool to be secured in the mandrel, and a needle secured in the other of said tubes and extending lengthwise thereof and adapted to enter between the free end-portion of said tool and the wall of said inner tube, for the purpose set forth.

4. A mandrel for the purpose set forth, comprising telescoping tubes, the inner one of which is open at both ends for receiving the tool to be secured in the mandrel, the inner end of said inner tube being beveled, and a needle secured in the other of said tubes and extending lengthwise thereof and adapted to enter between the inner portion of said tool and the wall of the inner beveled end of said inner tube, for the purpose set forth.

5. A mandrel for the purpose set forth, comprising tubes adapted to telescope one with the other and into one of which the tool to be secured is insertible, and means carried by said mandrel operating upon the act of telescoping said tubes with a tool in place therein to clamp the tubes together and clamp said tool to the mandrel.

6. A mandrel for the purpose set forth, comprising a tube, a member adapted to telescope with said tube, a tool insertible with said member into said tube, and means for securing said tool in the mandrel.

7. A mandrel for the purpose set forth, comprising tubes adapted to telescope one with the other, the inner one of which is open at both ends for receiving the tool to be secured in the mandrel, and means carried by the other of said tubes operating upon the act of telescoping the tubes to clamp the tool to the mandrel.

8. A mandrel for the purpose set forth, comprising tubes adapted to telescope one with the other, the inner one of which is open at both ends for receiving the tool to be secured in the mandrel, and means carried by the other of said tubes operating upon the act of telescoping the tubes to enter said inner tube and clamp the tool to the mandrel.

9. A mandrel for the purpose set forth, comprising telescoping tubes, the inner one of which is open at both ends for receiving

the tool to be secured in the mandrel, said inner tube having a portion of the wall of its inner end cut away, and wedging means carried by the outer tube for frictionally holding the tool and tubes together, said wedging means being adapted to enter between the inner end-portion of said tool and

the wall of the inner tube opposing the cut-away portion thereof.

JOHN M. GILMORE.
